UNITED STATES PATENT OFFICE.

LOUIS A. GROSSMAN, OF NEW YORK, N. Y.

DISPENSING DEVICE FOR WRAPPING MATERIAL.

Application filed January 26, 1927. Serial No. 163,672.

My present invention relates generally to dispensing apparatus, and has particular reference to a device for dispensing wrapping paper and the like in a certain manner and at predetermined times.

My invention is designed primarily for use in retail stores, and it is a general object of the invention to provide a device which will overcome the possible temptation of sales people to pocket or fail to record money that is received for purchased articles.

My invention contemplates the provision of a device which will prevent a sales person from securing the necessary wrapper or wrapping paper for the articles purchased without first recording the amount of money received by virtue of the purchase in some manner. More particularly, it is an object of the invention to provide a device adapted to retain the wrapping paraphernalia in normally inaccessible condition, and to provide means whereby a person seeking to secure wrapping material must first record the sale before rendering the wrapping material available.

It is an important object of the present invention to provide this device in a form whereby the manipulation of a single element or member will automatically achieve the contemplated purposes.

One feature of my invention lies in providing a single control member which is movable from a normal into two different positions; in providing means operable by moving the control member into one of said positions for causing the wrapping material to become available; in providing means operable by moving the control member into the other position to effect the recordation of the sale; and in providing means which prevents movement of the control member into the delivering or dispensing position until after it has been moved into the recording position.

Another object of the invention is to render the dispensing of the wrapping material entirely automatic when the control member is moved into the dispensing position. More particularly, my invention contemplates the provision of a driving source such as a motor, and an arrangement whereby a continuous length of wrapping paper or the like may be continuously fed from the device by the motor as long as the control member is in the dispensing position.

It being planned that the sales person will thereupon tear off the desired length which he has rendered available, it is another object of the invention to prevent a sales person from thereafter utilizing only portions of the available length without attracting the attention of either the purchaser or the subsequent attention of some person in higher authority.

Another object is to provide a device of the general character referred to wherein means are provided for achieving the same general purpose in connection with paper bags or other similar wrapping devices other than a continuous roll of material.

Another important object of the invention is to provide means for enabling the operator to render available a particular one of a selection of varied sizes of paper.

Other features of my invention lie in the particular arrangement and construction of parts which render the device as a whole particularly efficient, easy to manipulate, and reliable.

For the attainment of the foregoing objects and such other objects as may hereinafter appear or be pointed out, I have illustrated one form of my invention in the accompanying drawings in which—

Fig. 1 is a plan view of a complete device embodying the features of my invention, the paper and certain parts being omitted for the sake of clearness;

Fig. 2 is an end elevational view taken from the left of Fig. 1, with the left end wall removed to disclose the interior;

Fig. 3 is a front elevational view of Fig. 1, with the front wall similarly removed;

Fig. 4 is a side elevational cross-sectional view taken substantially along the line 4—4 of Fig. 1, and showing in dotted lines the various positions of the control member;

Fig. 5 is an end elevational view taken from the right of Fig. 1, with the right end wall removed;

Fig. 6 is a fragmentary view on an enlarged scale of a portion of Fig. 5;

Fig. 7 is a fragmentary plan view of the mechanism shown in Fig. 6;

Fig. 8 is a fragmentary cross-sectional view taken substantially along the line 8—8 of Fig. 7;

Fig. 10 is a plan view upon an enlarged scale of the parts which initiate the operation of the dispensing mechanism;

Fig. 11 is an enlarged end view of a portion of the device shown in Fig. 1, this view being taken substantially along the line 11—11 of Fig. 1;

Fig. 12 is an elevational cross-sectional view of a portion of the devices shown in Fig. 10, taken substantially along the line 12—12 of Fig. 10;

Fig. 13 is a view similar to Fig. 12 taken substantially along the line 13—13 of Fig. 10;

Fig. 14 is an enlarged end view of one of the elements of Fig. 10 taken substantially along the line 14—14 of Fig. 10.

Fig. 15 is a fragmentary front elevational view of a portion of the paper releasing mechanism.

Fig. 16 is a bottom view of the paper bag device;

Fig. 17 is a fragmentary plan view of a portion of the same mechanism;

Fig. 18 is a plan view of a portion of the device of Fig. 1, certain parts being omitted to disclose the disposition of the two sizes of continuous wrapping paper and to disclose the disposition of the paper bag device of Figs. 16 and 17;

Fig. 19 is an enlarged cross-sectional end view of a portion of the paper dispensing apparatus; and

Fig. 20 is a plan view of one of the elements of Fig. 19.

Referring now to the drawings, and particularly to Fig. 1, I shall briefly point out the general characteristics and relative positions of the various elements of the embodiment therein illustrated, it being understood that the particular arrangement and mountings shown are not essential except as otherwise pointed out herein.

I have shown my device mounted in a container having a base 25, front and rear walls 26 and 27 respectively, and side walls 28 and 29. Extending between the walls 26 and 27 are two spaced guide bars 30 and 31 upon which a movable carriage is designed to be supported so as to be movable backward or forward into various positions. This carriage is indicated generally by the reference numeral 32 and may be provided with a handle or grip 33 by which it may be pulled forwardly or pushed backwardly. Mounted upon the carriage 32, and designed to move therewith, is a printing device 34, herein illustrated as embodied in an adding or registering instrumentality similar to the ordinary cash register device. Also carried by the carriage 32 is the control member 35 provided at its forward end with a hand knob 36. To the rear of the member 35 is the mechanism which initiates the paper dispensing operation; and the member 35 is so arranged and constructed that pressure for-

wardly or downwardly upon the knob 36 will effect a printing upon material beneath the carriage, and movement of the member 35 in the opposite or rearward direction will effect certain movements of the initiating apparatus.

Immediately to the left of the carriage is the apparatus which is actuated by the mechanism to the rear of the member 35, and still further to the left I have illustrated a possible mounting of a motor 37 and a starting rheostat 38.

The present device is designed for use with two sizes of continuous wrapping paper, and also for use with paper bags. Two rolls of wrapping paper, of different widths, are designed to be supported or mounted in some position above the left-hand portion of the device. It may be stated generally that the paper is led, by means of rollers, toward the right, beneath the carriage 32, and thence out through the side wall 29. Similarly, the paper bags are designed to be fed upon a platform 39 which is movable rearwardly from the position shown in Fig. 1 so as to position a bag beneath the carriage 32. After the printing has been effected, the bag is discharged by an outward or forward movement of the platform 39. In Fig. 3, the general passage of the continuous wrapping paper through the device is more clearly disclosed, two continuous rolls 40 and 41 being shown as emanating from a source (not shown) and passing through the device in the general manner described.

Reference to Fig. 3, and also to Fig. 5, will indicate the general arrangement of the rollers. Two sets are provided, one set on each side of the carriage 32. Each set consists of a pair of spaced driving rollers and a movable idler therebetween. Thus, in Fig. 3, the two driving rollers of one set are designated by the reference numerals 42 and 43, and the corresponding driving rollers of the other set are designated by the reference numerals 44 and 45. Between the rollers 42 and 43 is a somewhat smaller idler 46, and a corresponding idler 47 is mounted between the rollers 44 and 45.

Before proceeding to describe the mounting of the rollers in greater detail, I will explain that the rollers 42 and 44 are designed to rotate continuously in a counter-clockwise direction as viewed in Fig. 3, whereas the rollers 43 and 45 are designed to rotate continuously in a clockwise direction. The idlers 46 and 47 are so mounted as to be normally out of contact with the driving rollers, but means are provided for moving the idlers 46 and 47 in unison either upwardly or downwardly so as to effect contact with either the upper set or the lower set of driving rollers. One length of paper, such as the paper 40, is designed to pass be-

tween the upper set of driving rollers 42, 44 and the idlers 46 and 47; whereas the other length of paper (41) is made to pass between the lower set of driving rollers 43, 45 and the idlers. In this way, when the idlers are moved upwardly, the paper 40 is frictionally engaged and caused to move toward the right; similarly, when the idlers are moved downwardly, the paper 41 is frictionally engaged and caused to move in a similar manner.

In Fig. 5, I have shown how the driving rollers are mounted in upright standards supported upon the base 25. In this figure, the rollers 44 and 45 are clearly shown mounted in upright standards 48 and 49; and it will be understood that the rollers 42 and 43 are similarly mounted. To effect the continuous rotation of the rollers in the manner described, I have provided two intermeshing gears 50 and 51 mounted upon the ends of the rollers 44 and 45 respectively. Two similar gears, of which the uppermost gear 52 is clearly shown in Fig. 1, are mounted upon the ends of the rollers 42 and 43. At the opposite end of each of the rollers 43 and 45 I have mounted beveled gears 53 and 54 respectively, these gears being driven by a transverse shaft 55 upon which are mounted two beveled gears 56 and 57; the gear 56 meshing with and driving the gear 53, and the gear 57 meshing with and driving the gear 54. The shaft 55 is driven from the motor, and I have illustratively shown a worm drive connection 58 (Fig. 1) by means of which the rotation of the motor shaft 59 is imparted at a reduced speed to the shaft 55.

The idlers 46 and 47 are not mounted directly in the standards which support the driving rollers, but are mounted in vertically adjustable plates supported in a guided manner upon said standards. This mounting is shown in Fig. 3, but is more clearly disclosed in Fig. 19. Referring for the moment to Fig. 19, it will be observed that I have shown the standard 48 upon an enlarged scale, and also the corresponding standard 60. The rollers 44 and 45 are mounted in the standard 48, and the rollers 42 and 43 are mounted in the standard 60.

Referring first to the standard 60, it will be noted that two angular flanges 61 and 62 are provided which form a vertical guide-way between and underneath them. These flanges are more clearly observed in Fig. 18, and in this figure it will be noted that each of the four standards is provided with a similar set of flanges. Mounted for vertical reciprocating movement between the flanges 61 and 62 is a strip 63 having an opening therethrough in which the idler 46 is journaled. Above and beneath the bearing for the idler 46 are elongated vertical slots 64 and 65 which permit the passage

of the end journals of the driving rollers 42 and 43 therethrough. In this way, the plate 63 may be moved upwardly or downwardly without interfering in any way with the free rotation of the driving rollers 42 and 43.

To effect the upward and downward movement of the strip 63, I have provided at the top thereof a rack portion 66 meshing with a small spur gear 67. The gear 67 is journaled in the standard 60 and is mounted at the end of an actuating shaft which will be presently described. The invention contemplates a slight angular rotation of this actuating shaft in either one or the other direction at predetermined times so as to effect an upward or downward shifting of the strip 63.

So that the strip 68 mounted upon the standard 48 and corresponding to the strip 63 may be moved upwardly or downwardly along with the strip 63, I have provided a linking mechanism which is clearly shown in Fig. 19. The lower end of the strip 63 is provided with a second rack portion 69 meshing with a small spur gear 70. The latter is mounted upon a stub shaft to which is rigidly connected a small link 71. A rack portion 72, corresponding to the portion 69, is provided on the lower end of the strip 68, and a small spur gear 73 is in mesh therewith and similarly connected with a small link 74. The free ends of the links 71 and 74 are pivotally connected by a tie rod 75, so that upward or downward movement of the strip 63 will effect a small rotation of the gear 70, hence a slight pivotal movement of the link 71, and hence a slight horizontal shifting of the rod 75. The latter movement will rotate the gear 73 sufficiently to move the strip 68 along with the strip 63. A similar arrangement of racks, gears, and links is provided in the remaining two standards.

Having thus described the continuous rotation of the driving rollers, and the means for lifting and lowering the idlers, I shall now describe the means for effecting the vertical shifting of the strips 63, 68, etc. at predetermined times.

Referring to Figs. 10, 11, and 13, it will be observed that the spur gear 67 is mounted upon the end of an actuating shaft 76. Rigidly connected to this shaft, substantially midway thereof, is a rod 77 associated at its outer end with a rocking beam 78. The latter is pivotally mounted midway thereof in a small standard 79, and it will be readily understood that when the beam 78 is rocked, the arm 77 will be moved upwardly or downwardly about its point of attachment with the shaft 76 as an axis, thereby imparting the desired rotative movement to the actuating shaft 76.

Inasmuch as the rotative movement of

the shaft 76 in one direction will effect a feeding of one paper strip 40 or 41, whereas a rotative movement in the other direction will effect a feeding of the other paper strip, 5 it follows that the rocking of the beam 78 in one or the other direction will have to be effected in accordance with the particular paper strip desired. In Fig. 11, I have shown a leaf spring 80 medially attached 10 to the standard 79 and bearing upon opposite ends of the beam 78 so as to keep the latter normally in a horizontal position. Adjacent to each end of the beam 78 I have provided a depending roller, each of these rollers being 15 designed to be actuated by a latch movable transversely to the beam 78 and beneath the roller. One roller 81 is positioned so as to be actuated by a latch 82, and the other roller 83 is positioned at the opposite end of 20 the beam 78 so as to be actuated by a latch 84.

In Fig. 10, the latches 82 and 84 are clearly shown in their normal positions, and the latch 82 is more clearly shown in elevational 25 cross-section in Fig. 12. Referring to the latter figure, it will be observed that the latch comprises a forward portion whose upper surface 85 is beveled so as to facilitate the interposition of the latch beneath the 30 roller 81. In dotted lines, the latch is shown so interposed, and it will be readily understood that by virtue of the interposition the roller 81 will rise, pushing its end of the beam 78 with it against the action of the 35 spring 80, thereby effecting a predetermined rocking of the beam 78.

The latch 82 is mounted in a sheath or sleeve 86 having a bifurcated forward end between which the forward end of the 40 latch is disposed. The sleeve 86 is fixed in position, and is provided with a slot 87 in its upper face through which a pin 88 carried upon the top of the latch 82 projects. The slot is so arranged that the latch may 45 move in the contemplated manner relative to the sheath 86. Mounted upon the top of the sheath 86, and directly to the rear of the slot 87, is a pin 89; and between the pins 88 and 89 a tension spring 90 is arranged which 50 tends normally to hold the latch in its rearward (full line) position. The rearward movement of the latch may be limited by providing a shoulder 91 upon the latch itself, but it might also be limited by the abutting 55 of the pin 88 against the rear end of the slot 87.

The latch 84 is similarly constructed and mounted, as shown in Fig. 10, and each sheath is open at its rear end so that an 60 actuating block may be moved against the rear end of the latch to push it forward. I have shown one such block 92 positioned so as to push the latch 82, and I have shown a similar block 93 positioned so as to move the 65 latch 84.

Inasmuch as the movements of the blocks 92 and 93 fulfill the additional function of starting the motor, I shall now describe these blocks more fully, together with their 70 mountings.

Referring again to Fig. 1, it will be noted that I have provided a long medially pivoted rod 94 arranged in substantially parallel relation to the actuating shaft 76 and positioned slightly to the left of the rocking beam 78. I have shown the rod 94 pivotally mounted as at 95, and I will point out that the rear portion thereof is designed to be forced to the left (in Fig. 1) when either of the blocks 92 or 93 is similarly moved. 75 The forward portion of the rod 94 is designed to fulfill two functions, one of which is to start the motor. In contemplation of this function, I have provided a connecting link 96 supported upon the forward portion 80 of the rod 94, this link being shown in Fig. 1 as leading to the rheostat 38. When the rod 94 is pivoted about the point 95 by pressure to the left upon a portion of its rear end, the forward portion of the rod 94 will 90 move to the right and will thereby pull the link 96 and actuate the rheostat 38.

Referring again to Fig. 10, it will be noted that each of the blocks 92 and 93 is mounted 95 upon the inner end of an arm which is slidably mounted to move in a direction substantially parallel to the movement of the latches. The block 92 is mounted upon the end of an arm 97 whose outer end 98 abuts a portion of the rear end of the rod 94. 100 Similarly, the block 93 is mounted upon the end of an arm 99 whose inner end 100 similarly abuts a portion of the rod 94.

The invention contemplates that either one of the blocks 92 and 93 will be forced 105 to the left by mechanism presently to be described. This mechanism has a predetermined movement, and it will therefore be obvious that the thickness of the block 92 must be greater than that of the block 93, 110 so that the pivotal movement of the rod 94 will always be the same.

Before proceeding to describe the balance of the mechanism, it will be understood that movement of either of the blocks 92 or 93 115 will (a) start the motor, and (b) actuate one of the latches 82 or 84. If the block 92 is pushed, the latch 82 will be actuated, the beam 78 will be rocked in one direction, the actuating shaft 76 will be rocked accordingly, and the idlers 46 and 47 will be moved in an upward direction. Similarly, if the block 93 is pushed, the shaft 76 will be rotated in the opposite direction and the idlers will be lowered.

To effect the return of the rod 94 to its normal position, when pressure upon either of the blocks 92 or 93 is released, a spring 120 101 (Fig. 1) may be provided at the rear end of the rod 94.

The mechanism which pushes either of the blocks 92 or 93 comprises a plunger 102 transversely mounted upon the carriage 32 and movable to the left, i. e., against the desired block 92 or 93, by a rearward movement of the control member 35. I shall now describe the mechanism which effectuates this movement of the plunger 102, it being understood that when the plunger is moved, 5 the motor will be started, and a desired type of paper will be fed from the machine.

Referring particularly to Figs. 2 and 5, it will be observed that the rear end of the control member 35 is pivoted in a supporting standard 103. Coincident with the pivot axis is a shaft 104 rotatable by pivotal movement of the control member 35. At one end of the shaft 104, a segment 105 is mounted comprising a substantial semi-circle and having the rear portion thereof toothed as shown at 106 in Fig. 5. Meshing with the teeth 106 is a spur gear 107, the latter being mounted upon a transverse shaft extending across the carriage 82.

25 Referring now to Fig. 10, it will be observed that the shaft upon the end of which the spur gear 107 is mounted is medially shaped in the form of a screw 108 of very large pitch. Engaging and embracing this screw portion 108 is the forward end 109 of a transversely movable arm 110 extending rearwardly and downwardly and terminating at its rear end in a sleeve portion 111, the latter being mounted upon and rigidly 30 secured to the plunger 102. The securing of the portion 110 to the plunger 102 may be effected by means of a set screw 112 or the like, and when a set screw is employed, one end of a coil spring 113 may be attached 35 to said set screw, the other end of the spring being rigidly secured, as at 114, to a fixed portion of the carriage.

The forward portion 109 of the arm 110 is internally threaded so as to mesh with the screw portion 108. In this way, the slight 45 rotation imparted to the spur gear 107 by the rearward movement of the control member 35 will be sufficient to cause the arm 110 (and the plunger 102 with it) to move 50 transversely across the carriage from the full line position of Fig. 10 to the dotted line position thereof. In this way, the plunger 102 is caused to move to the left to press upon whatever block is in its path.

55 An important feature of the invention lies in preventing a rearward movement of the control member 35 before the printing or recording operation has been effected. The latter operation may be effected in any 60 desired manner and is initiated in the present embodiment by a forward or downward movement of the control member 35. I shall therefore proceed to describe the mechanism whereby rearward movement of the control member 35 is prevented until after said

member has been moved forwardly or downwardly.

This mechanism is clearly disclosed in Figs. 5, 6, 7, and 8. In Fig. 5, the control member 35 is shown in its normal position, and rearward movement thereof is prevented as follows: Arranged upon the segment 105 is a tooth 115 whose forward face 116 is arranged along a substantially radial plane, and whose rear face is inclined. The forward face 116 is designed to engage a juxtaposed and similarly constructed face of a tooth 117 provided upon the top surface of an adjustable plunger 118. The latter is more clearly disclosed in Fig. 7 wherein it will be observed that it comprises a forward portion 119 within which the tooth 117 is mounted, the portion 119 being guided for reciprocating movement between two juxtaposed guides 120. The plunger 118 extends rearwardly through suitable guides, the rearmost of which is designated by the numeral 121, and the plunger is provided at its rear end with an enlarged portion 122 which limits its forward movement.

A compression spring 123 mounted between the forward portion 119 and the intermediate guide tends normally to hold the plunger 118 forwardly in its normal position shown in Fig. 5, this normal forward urging being limited by the enlarged rear portion 122. In this normal position of the plunger, the segment 105 is prevented from rotating so as to actuate the gear 107. However, if the control member 35 is first moved forwardly or downwardly, a projection 123 carried by the segment 105 will bear against the forward portion of the plunger 118 and will push it rearwardly. In Fig. 5, the projection 123 is shown in its normal position, and in Fig. 6, the control member 35 has been moved forwardly to an extent wherein the projection 123 has forced the plunger 118 rearwardly to its full extent. In this rear position, the plunger is locked by means of the latch rod 124 (Fig. 7), the rod 124 being forced into a suitable opening 125 in the rear portion of the plunger 118 by means of the compression spring 126.

The plunger having been locked in this rear position, the control member may be moved rearwardly to its fullest extent so as to effect a movement of the plunger 102 and a consequent initiating of the paper dispensing operation, it being understood that in the locked rear position of the plunger 118, the tooth 117 is out of the path of the tooth 115. When the control member is moved rearwardly, and when the arm 110 is accordingly moved transversely across the carriage, a small projection 127 carried by the arm 110 encounters a collar 128 upon the latch rod 124 and causes the latter to release the plunger 118. When the latter is released, the spring 123 will urge it forwardly

into its normal position. In order that the segment 105 may thereupon be brought back to its normal position of Fig. 5, the tooth 117 is constructed as shown in Fig. 8. In this figure, it will be observed that the normally visible portion shown in the other figures is merely the upper portion of a pivoted member held in a normally vertical position by a compression spring 129. When the segment is returned to its normal position, after the dispensing operation has been completed, the tooth 115 will ride over the tooth 117, pivoting the latter against the action of the spring 129. Immediately thereafter, the tooth 117 will snap back into its normal position and will thereafter again prevent rearward movement of the control member 35 until after forward movement has taken place.

The forward movement of the control member 35 may be made to record or print in any desired manner. In the embodiment shown, manipulation of the levers 130 (Fig. 1) of the registering device 34 will position certain predetermined printing types 131 (Fig. 9) in a horizontal plane directly over the paper beneath the carriage 32. Forward movement of the lever 35 will force the entire device 34 downwardly so as to impress the types 131 upon the paper beneath. The downward movement of the device 34 may be effected by means of a pin 132 mounted upon the control member 35 slightly in advance of its pivot axis and engaging in an elongated slot provided in a link 133 pivotally mounted on top of the device 34. When the pin bears down upon the lower end of the slot, it will transmit the downward pressure of the member 35 through the link 133 to the entire device 34. The elongation of the slot in which the pin 132 is located permits the control member to be moved rearwardly. Suitable spring means are provided, together with suitable mounting arrangements for the device 34, so that this device will be normally in the full line position of Fig. 4, the downward pressure of the control member 35 into the lower dotted position of Fig. 4 functioning to force the device 34 downwardly into the dotted position. In this dotted position, the types 131 are brought down upon the paper beneath the carriage.

In order that the paper may be normally inaccessible, I provide a raisable shearing bar 134 normally resting upon the wall 29 and adapted to permit the paper to be fed outwardly through the space between the wall 29 and itself, when it is raised. In order to effect the raising, I have mounted the bar 134 upon vertically movable guides provided at their lower ends with rack portions 135 (Fig. 15). Each of these rack portions is actuatable by a spur gear 136, rotation being imparted to these spur gears by

links 137, the latter being operatively associated with the pivotal bar 94. More particularly, upon referring to Figs. 1 and 3, it will be noted that a link 138 extends between the forward portion of the bar 94 and the upper portion of a pivoted lever 139, the lower end of the latter being connected to the link 137.

The carriage upon which the device 34 and the mechanism to the rear thereof is mounted is shown in greater detail, in a view taken from underneath, in Fig. 9. Suitable rollers 140 are provided so as to guide the carriage along the guide rods 30 and 31. Suitable hooked portions 141 may be provided adjacent to the rollers 140 so as to prevent upward movement of the carriage from off the rods 30 and 31.

The invention contemplates that the carriage will be fixed into that particular position in which actuation of the control member will print upon and release the desired type of wrapping material. Thus, if the carriage is moved to its rearmost position, as shown in Fig. 1, the plunger 102 is located so as to actuate the block 92. In order to hold the carriage in this position, a latch 142 is provided which consists of a rod pivoted medially thereof as at 143, having its rear end turned outwardly to engage in any one of suitably provided fixed recesses 144, and the forward end of the rod 142 being normally held toward the left by means of a spring 145. A suitably arranged finger grip 146 may be provided adjacent to the handle 33 so that pressure upon the grip 146 will release the latch 142 until the carriage has been moved into the desired position. Release of the grip 146 will then cause the latch to snap into the proper recess 144 and retain the carriage in its proper position.

In accordance with the present invention, paper bags may also be dispensed in a similar manner, and for this purpose, the carriage is movable into a third position wherein the plunger will actuate neither the blocks 92 nor 93 but a third block 147.

The actuation of the block 147 has for its sole function the discharging of the platform 39, it being understood that no motor actuation is necessary, nor are any rollers necessary.

In Figs. 16, 17, and 18 I have illustrated the bag device more clearly, and I will point out that it consists essentially in means for retaining the platform 39 in an inward position, and means for thereafter, after the bag has been printed upon, releasing the platform 39 and permitting it to discharge into the normal position shown.

The platform 39 is mounted upon an end portion of the main printing bed 148, and is guided in its reciprocal movement by means of two pins 149 extending down-

wardly through parallel slots 150 in the bed. Carried by the pins 149 and extending transversely beneath the bed is a bar 151 provided at one end with a latch portion 152. The latch which engages the portion 152 when the platform 39 is pushed inwardly comprises a bell crank structure having one arm pivoted at 153, having one arm 154 extending in a transverse direction 10 and having the other arm 155 extending in a direction substantially parallel to the movement of the platform 39. The arm 155 is provided at its forward end with an enlarged latch portion 156. The forward 15 face of the latter is suitably configured so that rearward movement of the platform 39 will push the latch portion 156 outwardly, thereby permitting the latch portion 152 to pass. After the enlarged portion 156 20 has been passed, the latch will snap back to its normal position under the action of a spring 157 and firmly hold the platform in its inward position. This inward and locked position is shown in dotted lines in 25 Fig. 16.

The subsequent releasing of the platform 39 is effected by a pressure upon the arm 154 of the latch, and this pressure will be toward the left as viewed in Fig. 16. This 30 pressure is effected by means of a vertical lever 158 pivoted at 159. The lower end of the lever 158 engages the arm 154 of the latch, while the upper end is disposed in the path of a block 160 actuated by movement 35 upon the block 147. More particularly, upon referring to Fig. 1, it will be observed that the block 160 is mounted upon the end of a reciprocable rod 161 normally urged rearwardly by a spring 162. The block 147 40 comprises one arm of a bell crank lever whose other arm 163 abuts the end of the rod 161. Consequently, when the block 147 is pushed inwardly by the plunger 102, the rod 161 will be pushed forwardly, the block 45 160 will push upon the upper end of the lever 158, and the pivotal movement of the latter about the point 159 will cause a releasing pressure upon the arm 154 of the latch which is holding the platform 39.

50 The platform 39 is normally urged outwardly by a spring 164 supported at its rear end upon the rod 151. Where desired, a similar connection 165 between the rod 151 and a suitable counter 166 may be made 55 to record the number of bags operated upon by the device.

It will be understood that a bag placed 60 upon the platform 39 and pushed inwardly therewith will not again be accessible until after it has been printed upon, because the actuation of the block 147 will not be possible until after the control member 35 has been moved downwardly. In this respect, the functioning of the bag device is similar 65 to the functioning of the device in connec-

tion with wrapping paper. It will be understood that in the use of my device, the purchasers will probably be advised, as by notices or otherwise, of the necessity for examining the wrapping paper or bag to 70 see the amount of their sale impressed thereon. The possibility of having a purchaser report the fact that no sale has been recorded upon his bag will serve as a sufficient check upon the sales person to compel 75 the latter always to utilize the bag device.

As a further check upon the sales person and particularly with respect to the continuous wrapping paper, the shearing bar 134 is provided with a nick 167 so that both ends 80 of the wrapping paper, when torn off, will embody such a nick. The purchaser will be advised to look not only for the printed record of the sale, but also to examine the opposite ends of the wrapping paper to see 85 that they embody the designated nicks, it being understood that distinctive shapes or configurations of nicks may be provided so as to make this observation a simple one.

It will be obvious that many changes in 90 the details herein described and illustrated for the purpose of explaining the nature of my invention may be made by those skilled in the art without departing from the spirit and scope of the invention as expressed in 95 the appended claims. It is therefore intended that these details be interpreted as illustrative, and not in a limiting sense.

Having thus described my invention and 100 illustrated its use, what I claim as new and desire to secure by Letters Patent is—

1. In an apparatus for dispensing wrapping material, material-receiving means, means for discharging the material to render it available, and means for printing desired indicia upon the material; a control member movable into two different positions, means operable when the member is in one of said positions for initiating the material discharge, means operable when the member 105 is in the other of said positions for initiating the printing; and means for locking the member against movement into the discharge position until after it has been moved into the printing position.

2. In a paper dispensing apparatus, means for receiving varied types of paper, means for discharging paper of a selected type to render it available, and means for recording desired indicia on said paper; a control member movable into two different positions, means operable when the member is in one of said positions for initiating the paper discharge, means operable when the member is in the other of said positions for initiating the recording; means for locking the member against movement into the discharge position until after it has been moved into the recording position; and means for initially shifting the control member bodily 115 120 125 130

to render said functions operable in connection with the type of paper selected.

3. In a wrapping paper dispensing apparatus, a pair of spaced driving rollers, an 5 idler roller therebetween and normally out of contact with both driving rollers, means for moving said idler roller against either of said driving rollers so as to cause frictional engagement and consequent movement of any paper therebetween; printing mechanism adapted to print upon the paper to be dispensed, and means for locking said roller-moving means until after said printing mechanism has functioned.

15 4. In a wrapping paper dispensing apparatus, a pair of spaced driving rollers, an idler roller therebetween and normally out of contact with both thereof, means for directing two continuous lengths of paper between said idler roller and said driving rollers respectively, a pair of actuating blocks, means operable by the actuation of either of said blocks for moving the idler roller against one or the other of the driving rollers depending upon the actuating block functioning, an actuating plunger, means for initially moving said plunger into proximity with a selected block, whereby actuation of the plunger will thereupon cause 30 a feeding of a correspondingly selected length of paper; printing mechanism adapted to print upon said lengths of paper, and means for locking said plunger until after said printing mechanism has functioned.

5. A recording and dispensing device for paper bags or the like, comprising a normally accessible platform adapted to receive a bag thereon, means for moving and locking said platform in an inaccessible position within the device, a movable control member, means operable by one movement of the control member for releasing said platform, means operable by another movement of said 45 control member for effecting a recordation upon the bag, and means for locking the control member from movement into the release position before movement thereof into the recordation position.

50 6. In a paper dispensing apparatus, means for receiving varied types of paper, printing mechanism for printing upon the paper, and means for discharging paper of a selected type to render it available only after it has been printed on, said last named means comprising a series of movable blocks, an actuating member therefor, means for initially adjusting the member into operative relationship with a selected block, and means 55 for locking said actuating member until after the printing mechanism has functioned.

7. In a paper dispensing apparatus, means for receiving a plurality of continuous strips 65 of paper, mechanism for printing upon a

selected strip, and means for discharging a selected strip to render it available only after it has been printed on, said last named means comprising sets of driving rollers for engaging said strips respectively, a series 70 of movable devices operatively associated with the rollers and adapted to render respective sets thereof operative when the devices are moved, a common actuating member for said devices, means for initially adjusting said member into operative relationship with a selected device, and means for locking said actuating member until after the printing mechanism has functioned.

8. In a paper dispensing apparatus, means 80 for receiving a pair of continuous strips of paper, printing mechanism for printing upon a selected strip, and means for discharging a selected strip to render it available only after it has been printed on; said last named means comprising a pair of spaced driving rollers on opposite sides of said strips, an idler roller between said strips and movable into engagement with one or the other driving roller to engage one or the other strip therebetween, a pair of movable devices arranged and constructed so that movement of one or the other thereof will move the idler roller in one or the other direction, a common actuating member for 90 said devices, means for initially adjusting said member into operative relationship with a selected device, means for normally locking said actuating member against movement, and means operable upon functioning of the 100 printing mechanism for releasing said locking means.

9. In a paper dispensing apparatus, means for receiving a pair of continuous elements of paper, means for receiving cut elements 105 such as paper bags, mechanism for printing upon a selected element, and means for discharging a selected element to render it available only after it has been printed on, said last named means comprising driving rollers for engaging the continuous elements, a latchable supporting platform for the cut elements, spring means for urging the platform outwardly, a series of movable devices arranged and constructed in respective operative association with said rollers and platform, so that actuation of the proper device will cause the discharge of the corresponding element, a common actuating member for the 110 devices, means for initially adjusting the actuating member into operative relationship with a selected device, and means for locking said actuating member until after the printing mechanism has functioned.

10. In a paper dispensing apparatus, means for receiving varied types of paper, mechanism for printing thereon, and means for discharging paper of a selected type to render it available only after it has been 125 printed on, said last named means compris- 130

ing a series of movable blocks, an actuating plunger therefor, a movable carriage for supporting said plunger and so arranged that the plunger may be initially positioned 5 in operative relationship with a selected block, and means carried by the carriage for locking said plunger until after the printing mechanism has functioned.

11. In an apparatus for dispensing wrapping material, material-receiving means, means for discharging the material to render it available, and means for printing desired indicia upon the material; a control member movable into two different positions, means 10 operable when the member is in one of said positions for initiating the material discharge, means operable when the member is in the other of said positions for initiating the printing; and means for locking the 15 member against movement into the discharge position until after it has been moved into the printing position, said locking means comprising a pair of abuttable teeth one of which is associated with the control member, said teeth being normally positioned so as to prevent movement of the control member into the discharge position, and means 20 operable by moving the control member into the printing position for adjusting the teeth into non-abuttable relationship.

12. In an apparatus for dispensing wrapping material, material-receiving means, means for discharging the material to render it available, and means for printing desired indicia upon the material; a control member movable into two different positions, means 25 operable when the member is in one of said positions for initiating the material discharge, means operable when the member is in the other of said positions for initiating the printing; and means for locking the 30 member against movement into the discharge position until after it has been moved into the printing position, said locking

means comprising a pair of abuttable teeth one of which is associated with the control member, said teeth being normally positioned so as to prevent movement of the control member into the discharge position, and means operable by moving the control member into the printing position for adjusting the teeth into non-abuttable relationship, said last named means comprising a projection associated with the control member, and a reciprocable plunger carrying the second tooth and arranged in the path of said projection when the control member is moved into the printing position.

13. In an apparatus for dispensing wrapping material, material-receiving means, means for discharging the material to render it available, and means for printing desired indicia upon the material; a control member movable into two different positions, means 60 operable when the member is in one of said positions for initiating the material discharge, means operable when the member is in the other of said positions for initiating the printing; and means for locking the 65 member against movement into the discharge position until after it has been moved into the printing position, said locking means comprising a pair of abuttable teeth one of which is associated with the control member, said teeth being normally positioned so as to prevent movement of the control member into the discharge position, and means 70 operable by moving the control member into the printing position for adjusting and locking the teeth into nonabuttable relationship; and means for unlocking and restoring the teeth into normal position when the control member is moved into the discharge position.

In witness whereof, I have signed this specification this 25 day of January, 1927.

LOUIS A. GROSSMAN.
